George I. Gelder,
INVENTOR
BY Victor J. Evans
ATTORNEY

UNITED STATES PATENT OFFICE.

GEORGE I. GELDER, OF MILWAUKEE, WISCONSIN.

SHOE-STRETCHING STICK.

Application filed January 16, 1929. Serial No. 332,960.

This invention relates to devices for stretching or softening shoes, an object being to provide a stick for the use of shoe dealers and others for "easing" or "raising" the toe of a shoe, for stretching the vamp, and for "pounding" the upper of the shoe or the sole.

Another object of the invention is the provision of a device of the above character which is simple and economical in construction, efficient in use and may be used with shoes of widely different sizes.

With the above and other objects in view, the invention further includes the following novel features and details of construction, to be hereinafter more fully described, illustrated in the accompanying drawing, and pointed out in the appended claims.

In the drawing:—

20 Figure 1 represents a side view of the invention.

Figure 2 is a plan view.

Figures 3 and 4 are sections taken respectively on the lines 3—3 and 4—4 of Figure 1.

25 Referring to the drawings in detail wherein like characters of reference denote corresponding parts, the invention as shown comprises an elongated body or member 10 having straight parallel sides 11 and a curved

30 top and bottom. The top is formed of a compound curve and includes a raised portion or hump 12 and an inwardly curved portion 13. The bottom is also formed of a compound curve and includes an outwardly

35 extending portion or hump 14 and an inwardly curved portion 15. The ends of the stick terminate in curved extremities 16 and 17. The edges or corners of the stick are rounded as indicated at 18.

40 By reference to the drawing it will be seen that the invention provides a stick which may be formed of any suitable material such as hard wood, metal, etc., having a compound curved body with the height of the stick less

45 at one end than at the other.

In the use of the invention, the heavier end of the stick having the curved extremity 16 is used for men's shoes, while the opposite end is used for ladies' and children's shoes. The stick is inserted within the toe of the 50 shoe and is forced forward into the toe to ease or raise the toe and make the toe of the shoe a trifle longer. In this use of the invention, the hump or raised portion 12 or 14 of the stick is positioned downward or upon 55 the insole of the shoe.

For stretching the vamp of the shoe, the hump of the stick is turned upward and the stick is turned to the right and left, while to pound the shoe when stretching with a 60 stretching last, the curved portions 13 or 15 of the stick are used upon the vamp, and the flat sides of the stick are used to pound upon the soles.

Irrespective of which end of the stick is 65 used, the opposite end of the stick forms a convenient hand grip.

The invention is susceptible of various changes in its form, proportions and minor details of construction and the right is herein 70 reserved to make such changes as properly fall within the scope of the appended claims.

Having described the invention what is claimed is:—

1. A shoe stretching stick comprising an 75 elongated member having separate parallel sides, an upwardly curved top spaced from one end of said member, an inwardly curved bottom, and a rounded extremity at said end.

2. A shoe stretching stick comprising an 80 elongated member having separate parallel sides, a compound curved top and bottom defining reversely disposed humps spaced from opposite ends of said member with the height of the hump greater at one end than 85 at the other, and rounded extremities at opposite ends of the stick.

In testimony whereof I affix my signature.

GEORGE I. GELDER.
